UNITED STATES PATENT OFFICE.

HENRY BERTRAND AND FRANÇOIS VELUT, OF PARIS, FRANCE.

IMPROVEMENT IN PACKING FOR STEAM-PISTON AND OTHER RODS.

Specification forming part of Letters Patent No. 85,988, dated January 19, 1869.

To all whom it may concern:

Be it known that we, HENRY BERTRAND and FRANÇOIS VELUT, of Paris, in the French Empire, have invented a new System of Metallic Spring-Packings; and we do hereby declare that the following is a full, clear, and exact description thereof, which will enable others skilled in the art to make and use the same, reference being had to the accompanying drawings, forming part of this specification.

This invention relates to a metallic spring-packing which can be used on the cylinders of steam-engines and on other suitable machinery. It will form a perfectly-tight joint, and is intended as a substitute for the ordinary hemp packing, all leakage of the steam through the orifice of the piston-rod during the operation of the engine being effectively prevented.

In the accompanying drawings, Figure 1 represents a vertical longitudinal section of our improved elastic packing. Fig. 2 is a plan or top view of the same. Fig. 3 is a detail transverse section of the same, taken on the plane of the line $x\ x$, Fig. 2. Fig. 4 is a detail transverse section of the same, taken on the plane of the line $y\ y$, Fig. 2. Fig. 5 is a front view of the spring-plate by which the parts are forced together. Fig. 6 is a vertical longitudinal section of the inner part of the packing, the plane of section being indicated by the line $z\ z$ of Fig. 2.

Similar letters of reference indicate corresponding parts.

The spring-packing chiefly consists of two semi-cylindrical plates, A A, which, when put together, form a slotted cylinder, which is fitted into the box or head B of a steam-cylinder, as indicated in Fig. 1. The inner end of this slotted cylinder A A abuts against an annular plate, C, which is fitted between it and the box or head B, as shown.

An elastic washer, a , may be interposed between A and C, or B and C, as shown in Fig. 1. The outer end of the slotted cylinder A A is fitted through the tubular shank of a cap, D, which is placed with its shank into the head B, as shown. The inner end of the tubular shank b of the cap D is beveled to the inside, and fits against inclined shoulders $c\ c$ formed on the plates A.

E is a spring fitted upon the face of the cap D, and secured, by means of bolts $d\ d$ or other-

wise, to the box or head B. This spring serves to force the cap against the shoulders $c\ c$, to make a close joint between the inner ends of A and the plate C, and to exert a lateral pressure on the beveled shoulders c , whereby the two plates A are firmly forced against the piston-rod F, to make a secure packing where they touch said piston-rod.

The inner ends of the plates A A are enlarged to form an annular chamber, e , around the piston-rod. Into this chamber are fitted two curved plates, $f\ f$, which break the joints of the plates A, and which fit close against the inner shoulders g of said plates, as is clearly shown in the drawings. Their longitudinal displacement is prevented by pins $h\ h$ projecting from the plates A into the plates f , as in Fig. 6. The plates f are as thick as the chamber e is wide, so as to fill exactly the space they occupy between the plates A and the piston-rod.

The steam cannot enter the chamber e except where the plates f do not touch each other, their inner ends fitting close against the plate C, to partly close the annular space between C and F. The steam, entering the chamber e where the plates f do not come together, will be prevented from escaping between the plates A, as their joints are closed by f longitudinally, as well as on the shoulder g . The joint between the ring C and the box or head receiving the packing is a vulcanized-rubber or other washer, a .

When the packing is new the plates $f\ f$ touch with every point of their external faces the inner sides of the plates A in the chamber e , which they occupy within said plates A.

As soon as the wear resulting from the friction of the piston-rod has, by means of the cap D and spring E, necessitated the lateral closing together of the plates A in a horizontal direction, (the slot formed by them being above and below the piston-rod, as in Fig. 3,) the obturating-plates f , carried by these plates A, follow their motion, which they effect in a vertical direction, so that they will always continue to retain their relative positions within the chamber e , the wear of the piston-rod on the plates A and f being alike. The plates f still continue to fit against the plate C and shoulders g , as they cannot be worn out lengthwise.

In order to cause the aforesaid motion of

the plates A and f, the packing-cap D is provided with inclined edges at its inner end, which causes the plates A to draw near as the cap is pressed inward. A similar inclined plane is formed on the shoulder *c* of the plates A. The inclined plane is interrupted on two sides of the cap end, as is clearly shown in Figs. 2 and 6, so as to obviate the inconvenience of the differences in diameters resulting from the cap-hole, which ever continues the same, while the cylinder formed by the plates A changes its size as its inner side is being worn by the piston-rod.

The force with which the cap is to rest on the plates is regulated by the spring E. This spring is intended not only to prevent an excessive pressure, resulting from the tightening of the bolts *d*, if these were acting directly on the cap, but also (and this is the chief purpose) to cause a continuous pressure on the cap, and consequently to draw the plates A A closer together as they wear.

The plates A, for this reason, are not made to touch, but a certain play, *m*, is left between, which keeps diminishing with the wear, but which is very important, so that it must be renewed when, in consequence of the wear of the plates, it does no longer exist.

To prevent the spring from touching the piston-rod, the plates A may be made to extend or project beyond the cap and through the spring.

This metallic packing may be applied to any class of machines, whatever may be their forms and sizes, as it does not require the replacement of the cylinder-heads, and only necessitates the modification to be made in the cap which is to give it the incline whereby the plates A and the obturating-plates f are held in constant contact with the piston-rod.

Having thus described our invention, we claim as new and desire to secure by Letters Patent—

1. The plates A A and f f, constructed substantially as described.
2. The combination and arrangement of the plates A A and f f and spring E, substantially as set forth.

HY. BERTRAND.
VELUT.
